UNITED STATES PATENT OFFICE.

ANTHONY DONZEL, OF PHILADELPHIA, PENNSYLVANIA, ASSIGNOR TO
JOHN C. GRAHAM, OF SAME PLACE.

DESIGN FOR FRINGE.

SPECIFICATION forming part of Design No. 13,079, dated July 25, 1882.

Application filed June 10, 1882. Term of patent 14 years.

To all whom it may concern:

Be it known that I, ANTHONY DONZEL, of the city and county of Philadelphia, in the State of Pennsylvania, have invented and produced a new and original Design for Fringe, of which design the following is a specification.

The accompanying drawing is a side view of a section of fringe embodying and illustrating my design, which consists in a fringe having a heading, A, to which is attached a series of pendants, B, of substantially-cylindrical contour, each composed of chenille threads twisted helically about the axis of the pendant and projecting loosely therefrom. The fringe is ornamented by a series of figures having the

form of Greek crosses, each occupying portions of three or more pendants, and being formed of warp-threads of a color different from the ground or body color of the pendants, said figures being arranged in regular order throughout the length of the fringe.

I claim—

A design for fringe, consisting of a heading and a series of pendants ornamented by figures in the form of Greek crosses, of different color from the body of the pendants, substantially as set forth.

ANTHONY DONZEL.
